CLAIM

The ornamental design for charging apparatus, as shown and described.

DESCRIPTION

FIG. 1 is a front elevation view of a charging apparatus showing our new design;

FIG. 2 is a first side view of the design of FIG. 1;

FIG. 3 is a back view of the design of FIG. 1;

FIG. 4 is a second side view of the design of FIG. 1;

FIG. 5 is a front perspective view of the design of FIG. 1;

FIG. 6 is a side perspective view of the design of FIG. 1; and,

FIG. 7 is a top view of the design of FIG. 1.

The broken lines in the figures depict portions of the article which form no part of the claimed design.

1 Claim, 7 Drawing Sheets(56)
